REVERSIBLE PADDLE

Henry Singer, Honolulu, Territory of Hawaii, assignor of one-half to William S. Chang, Honolulu, Territory of Hawaii

Application October 16, 1939, Serial No. 299,734

1 Claim. (Cl. 273—97)

This invention relates to a reversible paddle and has for an object to provide a paddle and a resilient ball attached to the paddle by a cord, both sides of the paddle displaying preferably three distinctively colored playing areas on which 5 the ball must strike in sequence on one side, and then in sequence on the other side, thus promoting the skill and interest of the player.

A further object is to provide a reversible paddle of this type forming an interesting decorative toy which may be inexpensively manufactured.

With the above and other objects in view the invention consists of certain novel details of construction and combinations of parts hereinafter 15 fully described and claimed, it being understood that various modifications may be resorted to within the scope of the appended claim without departing from the spirit or sacrificing any of the advantages of the invention.

20 In the accompanying drawing forming a part of this specification:

Figure 1 is a perspective view of the reversible paddle, in use.

Figure 2 is a plan view of the reversible paddle showing the distinctly colored playing areas on 25 the face thereof.

Figure 3 is a longitudinal sectional view of the paddle showing the cord of the playing ball attached to the paddle at a point equi-distant from 30 the centers of the three distinctly colored playing areas on each face of the paddle.

Referring now to the drawing in which like characters of reference designate similar parts in the various views, 10 designates a paddle having a handle 11 integral therewith, the same being preferably formed of plywood, although other material may be employed. The paddle is substantially heart shaped, that is, is provided in its front edge with a recess having forwardly 35 diverging side walls 12.

An elastic cord 13 is secured to the paddle at the inner end of the recess by a staple 14 or other connection. The cord is equipped at the free end with a rubber ball 15 or other resilient ball, such as a tennis ball.

Each face of the paddle is marked with preferably three distinctively colored playing areas 16, 17 and 18, preferably respectively colored red, blue and white. The point at which the elastic cord is attached to the paddle is equally spaced from the central points 19, 20 and 21 of the 10 three playing areas.

Each face of the paddle is a duplicate of the other face so that the paddle may be reversed during play.

In playing the game the paddle may be manipulated to bounce the ball successively from the 15 playing areas, first from the red area, then from the white area and then from the blue area, on one side. Then the paddle is reversed and the same colored areas are again struck on the other 20 side by the ball on rebound, this procedure continuing from one side to the other, through any desired number of reversals of the paddle.

From the above description it is thought that 25 the construction and operation of the invention will be fully understood without further explanation.

What is claimed is:

A game apparatus comprising, a paddle having a handle, the paddle being heart-shaped and including two lobes having rounded oppositely disposed edges providing a recess between the lobes, a ball, and an elastic cord attached to the ball and secured at one end to the inner end of said recess, the rounded diverging edges of the lobes permitting the anchored end of the cord to swing laterally as well as vertically when the paddle is 30 35 swung up and down by its handle.

HENRY SINGER.
